UNITED STATES PATENT OFFICE.

WILLIAM D. DE LAMARTER, OF ELIZABETH, NEW JERSEY, ASSIGNOR TO ELLIOTT COMPANY, OF PITTSBURGH, PENNSYLVANIA, A CORPORATION OF PENNSYLVANIA.

TWIN STRAINER.

1,187,046.

Specification of Letters Patent. Patented June 13, 1916.

Application filed June 17, 1913. Serial No. 774,108.

To all whom it may concern:

Be it known that I, WILLIAM D. DE LAMARTER, a citizen of the United States, residing at Elizabeth, Union county, New Jersey, have invented a new and useful Improvement in Twin Strainers, of which the following is a full, clear, and exact description, reference being had to the accompanying drawings, forming part of this specification.

My invention has relation to multiple, or twin, strainers; and is designed to provide a strainer of this type of improved construction, also to provide a strainer of this type having a novel arrangement of valve and valve operating means whereby either side of the twin strainer may be closed off without interfering with the operation of the other side.

The nature of my invention will be best understood by reference to the accompanying drawings, in which I have shown a preferred embodiment thereof, and which will now be described, it being premised, however, that various changes can be made in the details of construction and arrangement of the parts without departing from the spirit and scope of my invention as defined in the appended claims.

Figure 1 of the drawing is a side elevation of a strainer embodying my invention. Fig. 2 is a vertical section of the same, and Fig. 3 is a top plan view with the cap plate removed.

In these drawings, the numeral 2 designates the casing of the strainer, which is divided interiorly to form two similar strainer chambers 3 and 4. Placed in each of these chambers is a foraminated filter cage or basket of any suitable character, one of these being shown at 5 in Fig. 2. These cages or baskets are removably seated in their respective chambers, each of the latter having an opening in its side wall through which the basket may be inserted and removed. These openings are normally closed by the doors 6 which are removably held in place by the pivoted clamp bars or straps 7 and clamping screws 8.

9 is a top cap plate, which is removably secured to the upper end of the casing, and 10 is a bottom cap plate which is secured to the lower end of the casing. The plate 9 has a water inlet connection at 11, while the top plate 10 has an outlet connection 12. In

the construction shown, the cap plates 9 and 10 are secured to top and bottom rings 13 and 14. The upper ring 13 with its cap plate incloses an inlet chamber 15; while the lower ring 14 and its cap plate incloses an outlet chamber 16. The chamber 15 communicates with the respective filter chambers by the ports 17 and 18; and these chambers communicate with the outlet chamber 16 by similar ports one of which is shown at 19 in Fig. 2.

20 designates a vertical shaft, which is journaled in suitable bearings 21 on the exterior of the casing. For convenience of construction, this shaft is shown as formed in two sections, the adjacent ends of the sections being squared as indicated at 22 and united by the hub portion 23 of an actuating lever or handle 24. This, however, is a detail construction, which is immaterial to my invention. Each end portion of the shaft extends through a suitable stuffing box or packing 25 into one side of the respective chambers 15 and 16, and carries within said chambers the crank arms 26 and 27. 28 is an inlet valve seated in the chamber 15 and arranged to control the ports 17 and 18.

29 is a similar valve seated in the chamber 16 and arranged to control the outlet ports 19. Each of these valves has a short stud or stem member 30, which engages an opening in the crank arm 26 or 27, whereby the valve will be moved with said arm. A spring 31 is interposed between each arm and its corresponding valve in order to hold the latter against its seat.

The operation will be readily understood. With the parts in the position shown, the two valves are in position to close the ports 18 and 19 of the filter chamber 3, while permitting free passage of water through the chamber 4. When the filter cage or basket in the chamber 4 becomes clogged so that it is desirable to remove it and clean it, the actuating lever or handle 24 is moved over to the right, thereby turning the shaft 20, and through the crank arms 26 and 27 shifting the valves to a position where they will close the ports 17 and 18 of the filter chamber 4.

It will be noted that the doors 6 are set at an oblique angle to each other and to the general vertical plane of the strainer, thus giving ample room between them for the

movement of the lever 24 and to permit the filter cages or basket to be removed through the doors without interference with the lever.

5 The advantages of my invention will be apparent, since it provides a twin filter of simple construction and in which by a simple movement of the single actuating lever the valves can be shifted so as to throw either chamber out of operation while permitting the operation of the other chamber.

10 If desired, the parts can be so constructed as to give the valves 28 and 29 the intermediate position which will permit both filter chambers to be operated simultaneously. In fact, this is possible in the construction shown, by leaving these valves in the intermediate position.

15 What I claim is:—

20 1. A twin filter having two filter chambers, an admission port communicating with one end of each of said chambers, an outlet port leading from the opposite end of each of said chambers, a valve member for controlling the inlet end of both of the chambers, a valve member for controlling the outlet end of both of said chambers, and actuating mechanism connected to said valve members and arranged to simultaneously shift both of said valve members to uncover the ends of one filter chamber when covering

the ends of the other filter chamber, the arrangement being such that the flow through the strainer as a whole is uninterrupted, substantially as described. 35

2. A twin filter or strainer having substantially parallel filter chambers, opening into an admission chamber at one end and into an outlet chamber at the other end, an inlet connection leading to the admission chamber, an outlet connection leading from the outlet chamber, a pivoted shiftable valve in each of the admission and outlet chambers, a crank member extending into each chamber and having an actuating connection therein with each valve, bearings on the exterior of the filter for said crank members, and an actuating handle forming a connection between the two crank members, whereby the two valves are simultaneously shifted to uncover both ends of one chamber when covering the ends of the other chamber, the arrangement being such that the flow through the strainer as a whole is uninterrupted, substantially as described. 40 45 50 55

In testimony whereof I have hereunto set my hand.

WILLIAM D. DE LAMARTER.
